UNITED STATES PATENT OFFICE.

HOWARD FOREST GORSUCH, OF FREDERICKSTOWN, OHIO, ASSIGNOR TO DEAN C. TALBOTT, OF GALION, OHIO.

CRANE.

Application filed February 24, 1921. Serial No. 447,394.

To all whom it may concern:

Be it known that I, HOWARD FOREST GORSUCH, a citizen of the United States, residing at Frederickstown, in the county of 5 Knox and State of Ohio, have invented a new and useful Crane, of which the following is a specification.

This invention comprehends certain new and useful improvements in work holding 10 devices, and it has for its primary object a novel apparatus designed particularly for use in hoisting an engine out of a motor vehicle and holding it in such position that a mechanic may work thereon to advantage, 15 although it is to be understood that the invention is not confined to this particular use but is applicable for holding various kinds of work other than an internal combustion motor.

20 A further object of the invention is an apparatus of this character embodying a vertically movable carriage supporting a work holding arm that is capable of movement about its longitudinal, horizontally disposed 25 axis whereby the work to be operated upon may be conveniently raised to and held at the desired elevation and while thus held may be turned to different positions by partially rotating the arm thereby making all 30 parts of the work easily accessible.

A still further object of the invention is an apparatus of this character which is devoid 35 of the usual overhead crane arm or hoisting chains or cables, the device thereby economizing space and making it useful in positions where an overhead arm would be in the way.

A still further object of the invention is an improved work elevating and holding crane in which the manually operable parts 40 are disposed in convenient relation to each other whereby a single workman may easily manipulate both the shaft for raising and lowering the carriage and the shaft for partially rotating the work supporting arm.

45 And the invention also aims to generally improve devices in this class so as to render them more useful and commercially desirable.

With these and other objects in view, as 50 will more fully appear as the description proceeds, the invention consists of certain constructions, arrangements and combinations of the parts that I shall hereinafter fully describe and claim, reference being

had to the accompanying drawings in 55 which—

Figure 1 shows, in elevation, a device constructed in accordance with the invention; Figure 2 is an elevation wherein the device is viewed at right angles to the showing of 60 Figure 1; Figure 3 is a section on the line 3—3 of Figure 1; Figure 4 is a longitudinal section taken through the carriage; Figure 5 is a section on the line 5—5 of 65 Figure 3.

The crane comprises a frame 1 including a base 2 from which a standard 3 extends vertically. The base 2 embodies longitudinal bars 4, connected by cross beams 5, and supported on castors 6, to the end that the frame may be trundled about. The standard 3 is made up of guides 7 connected by upper cross plates 8, the plates 8 supporting ties 9. The guides 7 are connected at their lower ends by cross plates 10 secured to the beams 5 of the base 2. Upright braces 11 extend between the bars 4 of the base and the forward guides 7. Horizontal braces 12 connect the bars 4 of the base with the lower plates 10 of the standard 3. The guides 7 are united intermediate their ends by cross pieces 14.

The guides 7 are disposed in pairs, one pair of guides supporting bearings 15. A shaft 16 is journaled in the bearings 15. A drum 17 is secured to the shaft and is located between the bearings 15. The shaft 16 may be operated by a removable crank 18. A latch 19 is pivoted to one guide 7 and is adapted to be swung over into supporting 85 relation with respect to a stop 20 on the said guide. See Fig. 2. When the latch 19 is supported on the stop 20, the latch projects into the path of the crank 18, the drum 17 being prevented from rotating. 90 There is a ratchet wheel 21 on the shaft 16. A dog 22 is pivoted to one bearing 15 and engages the ratchet wheel 21. The dog 22 and the ratchet wheel 21 hold the shaft 16 and the drum 17 against rotation. The dog 95 22 and the ratchet wheel 21 are of use, when the crank 18 (which cooperates with the latch 19) is removed, and when a finer adjustment is desired, than can be obtained by permitting the crank 18 to swing through an arc of three hundred and sixty degrees, into engagement with the latch 19.

The crane embodies a vertically movable

carriage whereon the engine which is to be repaired is supported. The carriage 23 is made up of side rails 24 connected at the front side of the carriage by a top bar 25, 5 an intermediate bar 26 and a lower bar 27. The side rails 24 are connected at the back side of the carriage by a tie 28. A bearing plate 29 is secured to the intermediate bar 26 and depends therefrom. Fig. 4. The 10 bars 26 and 27 are connected by a bearing plate 30. Offset brackets 31 are mounted on the intermediate bar 26 and extend upwardly to the top bar 25. Sheaves 32 are journaled on the brackets 31 and the top bar 25. 15 A sheave 33 is supported for rotation between the ties 9 of the main frame 1. A sheave 34 is supported for rotation in bearings 35 erected on the ties 9. One end of a cable or other flexible element 36 is secured 20 as shown at 37 to the parts 9. The flexible element 36 is looped downwardly around one sheave 32 on the carriage, upwardly around the sheave 33 on the frame, downwardly around the other sheave 32 on the carriage, 25 and upwardly around the sheave 34 on the frame, the outer end of the flexible element being made fast to the drum 17.

Shafts 38 are journaled in the side rails 24 of the carriage 23 and carry rollers 39 30 disposed between the guides 7, the rollers having flanges 40 which, cooperating with the inner surfaces of the guides 7 (Fig. 1), aid in holding the carriage 23 for right line sliding movement in the guides 7. The shaft 35 41 is located parallel to the shafts 38 and is journaled in the members 24 of the carriage 23. The shaft 41 may be operated by a detachable crank 42. A worm 43 is mounted on the shaft 41 within the contour of the 40 carriage 23. The worm 43 meshes with a worm wheel 53 secured to a work supporting shaft 44 disposed at right angles to the shaft 41. An upwardly inclined supporting plate 46 is connected at its lower end to the 45 lower bar 27 of the carriage. Hangers 47 extend between the outer end of the plate 46 and the bar 26 of the carriage. The hangers 47 are connected to the plate 46 by securing elements 49 supporting a bearing 48. 50 The arm or shaft 44 is journaled in the bearing 48, in the bearing plate 30, and in the bearing plate 29. The parts 46 and 47 may be described briefly as a bracket projecting outwardly from the carriage 23 and supporting the shaft 44 for rotation. Endwise movement of the shaft 44 is prevented by a set collar 45 on the shaft, engaging the bearing plate 30, and by the hub of the worm wheel 53, the hub cooperating with the bearing plate 29. A pivot element 50 is mounted in the outer end of the shaft 44, and may be in the form of a clamping bolt. A cross head 51 is mounted to swing for adjustment 60 on the pivot element 50. A clamp 52 is 65 mounted in the cross head 51.

The engine which is to be repaired is clamped to the cross head 51 by the element 52. The shaft 16 is rotated by means of the crank 18. The flexible element 36 traverses the sheaves 32 and is reeled on the drum 17. 70 In this way, the carriage 23, together with the engine, is raised, the rollers 39 moving between the guides 7. The carriage 23 is held in any position to which it may have been elevated, either by engaging the dog 75 22 with the ratchet wheel 21, or by swinging the latch 19 into the path of the crank 18. The shaft 41 may be rotated through the medium of the crank 42, the worm 43 and the worm wheel 53 rotating the shaft 44, 80 the ends of the cross head 51, and consequently the ends of the engine, being swung around in a vertical plane. The cross head 51, further, may be swung on the pivot element 50. 85

The crane affords a simple means whereby an engine may be hoisted off the frame of a motor car and be disposed in a position which is convenient for the workman.

I claim:—

1. In a work holding apparatus, the combination of a vertically movable carriage, means for raising and lowering said carriage, an axially rotatable arm supported by and movable with said carriage, and means 95 for rotatively adjusting said arm.

2. In a work holding apparatus, the combination of a frame, a vertically movable carriage supported thereby, means for raising said carriage and holding it at different elevations, a work holding arm supported by said carriage and capable of a turning movement therein about its longitudinal axis, and means for turning said arm in the carriage. 100

3. In a work holding apparatus, the combination of a framework comprising a base frame and a vertically disposed frame, a carriage movable vertically in said vertical frame, means for raising and lowering said carriage in the frame, and for holding it at different elevations therein, a work holding arm revolvably supported by said carriage, and means for rotating said arm, such means being manually operable and carried 110 by said carriage. 115

4. A work holding crane comprising a framework, a carriage vertically slidable in said framework, and means for hoisting and lowering said carriage in the framework, 120 and holding it at different elevations, a horizontally disposed work holding arm journaled in said carriage and rotatable about its longitudinal axis, a worm wheel mounted in said carriage and operatively connected 125 to said arm, and a laterally disposed shaft journaled in said carriage and provided with a worm meshing with said worm wheel for rotating said arm.

5. An apparatus of the character described 130

comprising a framework including vertically disposed frame bars, a carriage mounted between said frame bars and provided with rollers engaging the latter whereby the carriage is mounted for a vertical sliding movement, sheaves mounted on said carriage, a cable connected to said framework and extending around said sheaves, and supported for running movement by the framework, work whereby to raise and lower the carriage, a drum carried by said framework and upon which one end of said cable is adapted to wind, manual means for rotating said shaft for raising and lowering the carriage, a work holding arm mounted for rotary movement about its longitudinal axis in said carriage, a worm gear operatively connected to said arm for rotating it a transversely extending shaft journaled in the carriage, and a worm carried by said shaft and engaging said worm gear for the purpose specified.

6. A work elevating and holding crane comprising a base mounted for movement upon a floor, a vertically disposed frame supported by said base, a carriage mounted for vertical movement in said frame, sheaves mounted upon said carriage, a cable connected at one end to said frame, sheaves carried by said frame above the carriage, said cable extending around the sheaves of the carriage and of the frame, a drum journaled in said frame, and to which the other end of said cable is connected, a manually operable shaft connected to said drum, a revoluble work supporting arm journaled in said car-

riage, a worm gear operatively connected to said arm, a laterally extending shaft journaled in said carriage, and a worm carried by said last named shaft and engaging said worm gear, as and for the purpose set forth.

7. A work holding apparatus including a wheel supported base having an upwardly extending standard, a vertically movable carriage supported on the standard, means mounted on the standard and operatively engaging said carriage whereby it may be moved vertically and held at different elevations, an axially rotatable work holding arm supported by said carriage and movable therewith, means for rotatably adjusting said arm, and work clamping means carried on the extremity of the arm.

8. A work holding apparatus including in combination a base and a vertically disposed standard, a carriage movable vertically on the standard, means on the standard for vertically shifting the carriage and for holding it at different elevations, a work holding arm mounted for axial rotation in said carriage, means for rotating said arm and holding it in rotatively adjusted positions, and work engaging means carried by the arm and rotatable therewith.

In testimony that I claim the foregoing as my own, I have hereto affixed my signature in the presence of two witnesses.

HOWARD FOREST GORSUCH.
